5,931

UNITED STATES PATENT OFFICE.

FREDERICK W. PORTER, OF SPRINGFIELD, VERMONT.

DESIGN FOR THE BODY OF A TOY-CARRIAGE.

Specification forming part of Design No. 5,931, dated June 11, 1872.

Specification for a Design for a Toy Carriage-Body, invented by FREDERICK W. PORTER, of Springfield, in the county of Windsor and State of Vermont.

The nature of my invention is fully represented in the accompanying photographic illustration, to which, with the letters marked thereon, reference is made.

F represents the carriage-body, the sides of which are cut in an ornamental form, as shown clearly at A, D, and A'. The ends of the body B and B' are plain pieces, which are secured between the side pieces near their ends, but at little distance therefrom, so that the ornamented ends of the side pieces may project beyond the plain or flat end pieces B and B' and show to good advantage; and the end pieces B and B' are placed in such position as to form an obtuse angle with the bottom of the body, as shown clearly by the photograph,

and the line of junction of the end piece B' with the side pieces is shown at C. The side pieces at the front end are a little higher than the edges of the end piece B', and at the rear end the end piece B is a little higher than the side pieces, as shown clearly in the photograph.

Having thus described my invention, what I claim as new, and desire to secure by Letters Patent, is—

1. The design for a toy carriage-body, substantially as shown and described.
2. The ornamented ends A and A' of the sides of the body, projecting beyond the end pieces B and B', both combined substantially as shown and described.

FREDERICK W. PORTER.
